WILLIAM P. HAMMOND AND THEODORE A. HAMMOND, OF PASSAIC, NEW JERSEY,
ASSIGNORS TO A. SCHRADER'S SON, INCORPORATED, OF NEW YORK, N. Y., A
CORPORATION OF NEW YORK.

PRESSURE-GAGE.

1,181,133.

Specification of Letters Patent.

Patented May 2, 1916.

Application filed April 29, 1910. Serial No. 558,413.

To all whom it may concern:

Be it known that we, WILLIAM P. HAMMOND and THEODORE A. HAMMOND, both citizens of the United States, and residents 5 of the city and county of Passaic and State of New Jersey, have invented the new and useful Improvements in Pressure-Gages, of which the following, taken in connection with the accompanying sheet of drawing, is 10 a specification.

This invention relates to new and useful improvements in gages, particularly intended to indicate fluid pressure, and more particularly to a coupling or connecting 15 means for gages.

The invention has for an object to provide in conjunction with a gage novel coupling or induct pieces in order to facilitate the application of the gage to the receptacle to 20 be charged or inflated under pressure.

With the above and other objects in view, the invention consists in the detail of construction, and in the novel combination of parts to be hereinafter referred to.

25 In describing the invention, reference will be had to the accompanying drawing forming part of this specification, wherein like characters of reference denote corresponding parts in the several views, and in 30 which—

Figure 1 is a longitudinal sectional view of the gage embodying the invention. Fig. 2 is a view partly in elevation and partly in section illustrating one form of coupling 35 piece. Fig. 3 is a view in elevation of the complete gage shown in Fig. 1. Fig. 4 is a longitudinal sectional view of another form of coupling piece.

In the drawings, —1— denotes a barrel 40 or cylinder closed at one end by the head —2—, and at the opposite end by the head —3—. The head —2— is provided with a stem —4— in which is provided a check valve —8— of any suitable construction 45 which will open to admit air to be forced into or through the device, but which prevents a reflux of the air.

Carried by the stem —4— and forming a continuation thereof is a tube or duct —19—

which passes through the barrel —1—. The barrel —1— telescopes into a shell or jacket —5—, which is formed with closed end —6—, the opposite end being open. The tube or duct —19— is surrounded by a stem —9—, the bore of the stem —4— forming about the tube —19— a pressure duct —10—. This stem —9— projects through the closed end —6— of the jacket —5—, and said projected portion —11— is screw-threaded exteriorly in order that it may be connected to the valve stem of the receptacle to be inflated if desired, but more particularly to the coupling pieces to be referred to. The stem —9— is held against displacement by the disk —12— which is locked to the 65 closed end —6— of the jacket —5— by the binding screws —13—. Near its outer end or the end adjacent the head —2— the stem —9— is provided with a head —14—, which bears against the inner wall of the barrel —1— and forms a pressure-head. Between the heads —3— and —14— is arranged a helical spring —15—, which holds the heads —2— and —14— normally in close proximity one to the other.

The jacket —5— is provided adjacent its inner or closed end —3— with a longitudinal slot —16—, and the exterior surface of the jacket along one edge of the slot is marked with a scale or graduation —17— indicating various degrees of air pressure in pounds per square inch or other suitable measure of pressure. The barrel —1— is provided with the encircling mark —18— which forms an index indicating on the 85 scale the degree of air pressure as the graduations come into registry therewith.

As above described, the device may be employed as a gage without the automatic blow-off or relief feature.

In the operation of the foregoing, the projected portion —11— of the stem —9— is attached to the valve stem or casing of the receptacle to be charged or inflated. At this point, particular attention is directed to the 95 cross-bar or pin —20— intersecting the bore of the projected portion —11—. This bar or pin —20— is intended to contact with

to depress and open the valve in the said valve stem as is believed to be apparent. If there be any air pressure in the receptacle, this pressure will be communicated through 5 the pressure duct —10— to the interior of the barrel —1— between the head —14— of the stem —9— and the head —2— of the barrel —1—. The barrel —1— will then move outwardly against the action of spring 10 —15— until the pressure of the spring counter-balances the air pressure. The graduation of scale —17— which thus registers with the encircling mark —18— will indicate the degree of pressure. If air is 15 to be forced into the receptacle, a pump is suitably coupled to the stem —4— and air is forced through the duct and the pressure of the air will be indicated in like manner. As the pressure in the barrel rises, the barrel 20 moves outwardly, the spring —15—, re-tracting the barrel as the pressure decreases.

It will be seen that the jacket —5— may be rotated independently of the various parts of the gage so that the scale —17— 25 may be brought into any position most convenient for reading without interfering with the connecting of the device with the valve stem of the receptacle, the encircling mark —18— permitting such reading. Another mode of use is to connect the same to one branch of a multiple branched connector as is shown in the drawings, whereupon the inflation pump may be connected to the free end of said connector and the pressure 30 gage caused to perform the added function of a pressure limiting device in the following manner: In order to automatically relieve the pressure after a pre-determined pressure has been obtained, the shell or 35 jacket —5— is embraced by a jacket —21—, which has its outer end closed as shown at —22—. Centrally of this closed end —22—, is arranged the pin —23—, threaded therethrough to project within the jacket —21—. 40 Should it be desired to inflate a receptacle to 30 pounds, the free or inner edge —24— of the jacket is brought into alignment with the “—30—” indication of the scale —17—, and the jacket —21— is then locked against 45 movement by the clamping nut —26— threaded to the stem —25—, projecting from the jacket —5— and passing through the slot —27— formed in the jacket —21—. As the pressure causes the barrel —1— to 50 move outwardly, the pin —23— will contact with and depress the valve —8— as soon as the mark —18— of the barrel —1— passes the “—30—” indication of the scale —17—. This will permit the escape of the 55 air or fluid, communication being had with the atmosphere through the opening —28— in the end —22— of the jacket. The pin —23— is threaded into place in order that a proper adjustment of the pin with rela-

tion to the stem of the valve —8— may be 65 had to assure a proper operation of the device.

For convenience of attachment to a receptacle, more especially to a pneumatic tire, when applied, either of the coupling pieces 70 or induct couplers shown in the drawings may be employed. The coupler —29— is arranged at right angles to the gage, and is provided with a central bore —30— having located in one end the check valve —31—, 75 to permit the forcing of air therethrough, but preventing the exit of air. The opposite end of the coupling is provided with a nipple —32— for connection with the valve stem of the receptacle, and may be of any 80 desired construction. The bore of the nipple is intersected by the pin or bar —33— for the same purpose as specified with relation to the pin —20—.

The coupler piece —29— is provided with 85 a boss —34— having a bore —35—, which may be provided with a check valve if desired similar to check valve —31—. Such a form is shown in Fig. 2. The bore —35— is adapted to register with the bore of the 90 projection —11— of the stem —9—. In order to afford such registry, the free end of the bore is provided with a threaded recess for the reception of the projected portion —11—. Bore —35— of the boss communicates with the bore —30—.

The operation of the device with the coupler piece attached, is thought to be obvious. In applying the gage, it is believed to be apparent that the pulsating pressure of the 100 pump is delivered directly into the receptacle. The gage is therefore affected by the still pressure in the receptacle. The coupler piece shown in Fig. —2— of the drawing is provided with an enlarged central portion 105 or chamber —36—.

The coupling piece shown in Fig. 4 comprises a plurality of branches —37—, each branch being provided with an inwardly opening check valve —38— in its passage-way, similar in construction to valves —8— and —31— heretofore described. The coupler is also provided with a nipple —39— which is provided with a valve opener similar to that shown at 20 in Fig. 1, for connecting the device to the valve stem casing of the tire. This form of connecting piece shown in Fig. —4— enables the pump to be attached to one branch, a pressure gage to another branch, and permits the release of 115 an excess of pressure upon the tire or receptacle to which it is attached by the depression or opening of the valve in the remaining or other branch.

When instantaneous gages are used, that 125 is, gages that are not coupled permanently and directly to the valve casing, but are merely held against the valve casing for a

moment, depressing the valve, and measuring the pressure thereby, we eliminate one of the branches shown in the coupling piece shown in Fig. 4, and use but two branches, one to which the pump connection is applied, and the other for the momentary application of the gage and the release of an excessive pressure when required.

While we have illustrated a preferred form of pressure gage coupling, we would have it understood that we are not limited to the details of construction shown and described, as the same may be varied and still come within the scope and tenor of the appended claims.

The pressure gage *per se* is claimed in our application, Serial No. 58,887, filed October 30, 1915.

The construction of coupling having means adapted to be operated to vent air while a gage is applied to the coupling, as shown for example in Fig. 4, is not claimed specifically herein, but forms the subject-matter of our divisional application, Serial No. 25 84,276, filed March 15, 1916.

Having thus described our invention, what we desire to secure by Letters Patent is,

1. In combination with a gage, an attaching device therefor, provided with a plurality of branches; check valves in said branches, and means for coupling the device to the valve casing of a pneumatic tire, and means for establishing open communication with the interior of the tire in the act of applying the device to the valve casing.

2. In combination with a gage, an attaching device therefor, comprising a body provided with passageways; check valves positioned in two end portions of the device, and an attaching nipple in the other end portion of the device, and means consisting of a rigid pin for engaging and depressing the valve of a pneumatic tire, and opening communication between the passageways and the interior of the tire in the act of applying the device to the valve casing of the tire.

3. In combination with the valve casing of a pneumatic tire, a connecting device comprising a body portion having a plurality of communicating passageways; check valves in said passageways; a coupling nipple carried by the body portion; and means for automatically depressing the valve of the valve casing in the act of applying the device thereto.

4. In combination with a pneumatic tire, a gage and a source of fluid-supply; a detachable connecting device consisting of a body portion provided with a plurality of passageways adapted to establish communication between a tire, gage, and source of fluid-supply; a plurality of check valves in said passageways, and an attaching nipple

carried by said device, provided with means for depressing the valve of the tire in order that the pressure therein may be indicated on the gage.

5. The combination, in an inflation connection for pneumatic tires, of a triple branched tubular body, one branch thereof being provided with a valve opening element and a valve nipple coupling, and each of the other branches being provided with an inwardly opening valve.

6. The combination of a pressure gage, means for supplying compressed gas, a conduit having terminals adapted to be connected one with said pressure gage and the other with said means, a valve in the pressure gage terminal, and means carried by said pressure gage for automatically opening said valve when said pressure gage is connected to said terminal.

7. The combination of a pressure gage, means for supplying compressed gas, a conduit adapted to be attached to a pneumatic tire valve and having means for unseating the valve member therein, and also having terminals adapted to be connected one with said pressure gage and the other with said gas supplying means, valves in said terminals and means carried by said pressure gage for automatically unseating the valve in that terminal with which it is connected.

8. A device of the character described having three branches, the first having means for connection with a gage, the second having means for connection with a pump or the like, and the third having means for connection with a tire valve, and an automatic check valve in said first-named branch.

9. A coupling device having a plurality of openings, one for connection with a gage and one for connection with a tire valve, and an automatic check valve located in said device near the point of connection with the gage and adapted to be closed when the gage is removed.

10. A device of the character described having three branches, the first having means for connection with a gage, the second having means for connection with a pump or the like, and the third having means for connection with a tire valve, and a valve in said first-named branch.

11. In a device of the character described, the combination of a part having a means for connection with a gage, a check valve in said part, a gage having means for unseating said valve, said part having also means for engaging a tube or the like, and means for engaging a tire valve or the like, said last-named means having a deflator for unseating the tire valve.

12. A coupling of the character described having a plurality of passageways greater

than two, one having a nipple of a diameter adapted to contact with the packing of a gage.

13. A coupling of the character described having a plurality of passageways greater than two, one having means for connection with a tire valve, and one having a nipple adapted to lead to the interior of a gage,

said nipple being of substantially the same diameter as said tire valve.
